UNITED STATES PATENT OFFICE

LOREN G. SYMONS, OF HOLLYWOOD, CALIFORNIA, ASSIGNOR TO SYMONS BROTHERS DEVELOPMENT COMPANY, OF HOLLYWOOD, CALIFORNIA, A CORPORATION OF DELAWARE

GRIZZLY BAR

Application filed December 17, 1930. Serial No. 502,914.

This invention relates to separating bars for employment with a separating deck in which bars with inter-penetrating arms and fingers are oscillated about parallel axes, and means are provided for causing movement of the material to be separated across the bars. One object is the provision of a separating member which shall be resistant to wear and to impact. Another object is the provision of such a member which shall be adapted to support particles above a predetermined size at a level above the apertures defined by the opposed bars and their arms and fingers.

Other objects will appear from time to time in the course of the specification and claims.

I illustrate my invention more or less diagrammatically in the accompanying drawings, wherein—

Figure 1 is a plan view;

Figure 2 is a partial plan view on an enlarged scale illustrating the bars in greater detail;

Figure 3 is a partial side elevation;

Figure 4 is a section on the line 4—4 of Figure 3;

Figure 5 is a section on the line 5—5 of Figure 2.

Like parts are indicated by like symbols throughout the specification and drawings.

Referring to the drawings, A generally indicates any suitable frame member, of which I show the side channel members A¹ A² which may be connected as by the transverse end members A³. In order to support the frame and screen at any desired angle, I may provide supporting abutments or brackets A⁴.

Mounted upon the upper flange of each channel A¹ A² are a plurality of boxes or housings, each formed by opposed angles B B¹, as shown for example in Figure 3 the top being closed by a cover plate B².

Positioned within the general rectangular

aperture so formed is a rectangular bushing or block B³ of rubber which is provided with a central aperture B⁴ herein shown as rectangular also. It will be clear, as from Figures 3 and 4, that both the block itself and the rectangular aperture are oblong or elongated with a long diameter generally perpendicular to the side frame member A¹ or A². The block B³ is preferably surrounded by a metal covering member B⁵ overturned at the sides as at B⁶ to prevent any undue lateral expansion of the block B³. The member B⁵ is split and the opposed edges are spaced slightly apart as at B⁷. The cover plate B² is provided with centering ears B⁸ between which passes a securing bolt B⁹, the ends of which pass through corresponding apertures in the angles B B¹, in which apertures are seated cone shaped bushings B¹⁰. The assembly is drawn together as by the nut B¹¹. The tapered bushings B¹⁰ have some wedging action and serve to seat the cover plate B² firmly against the top of the rubber block B³ and to maintain said block under a desired predetermined compression.

It will be understood that the blocks B³ are arranged in parallel or in definitely spaced relation along the opposite frame members. Threaded through each opposite pair of said blocks are separating bars. Each such bar includes a central bar C, the ends of which are upwardly built up as at C¹. The end with the upwardly built up portion seats in the aperture B⁴ of the rubber block B³. In each end of each bar is a socket or aperture C² which may receive a ball C³ opposed to an adjustable abutment C⁴ in a bracket C⁵, which may for example be welded to the upper flange of the channel member A¹ or A². The abutment C⁴ is herein shown as screwthreaded in said bracket C⁵ and is provided with an apertured disc C⁶ through which may be passed a cotter C⁷ which may penetrate the bracket C⁵ and thus prevent rotation of the

member C⁴ and thus hold it in any desired adjusted position. It will be noted that the center of rotation or oscillation of the bar C, as generally defined by the ball C³, is midway of top and bottom of the built up end portion of the bar.

Laterally projecting from opposite sides of each bar C are aligned arms D, the arms being provided with laterally extending fingers D¹. It will be seen as in Figure 2 that the arms D are generally perpendicular to the bars C and that the fingers D¹ are generally parallel with the bars C. The junction of arms and bars and of fingers and arms may be provided with fillets as at D², if desired. The upper surfaces of bars, arms and fingers are in general parallelism and are substantially below the tops of the built up portions of the ends of the bars as at C¹. In fact, the center of oscillation, as defined by the ball C³, is adjacent or, in the particular embodiment shown, only slightly below the effective upper surface of bars, arms and fingers. If desired, the bars may be formed of a softer or less resistant material than the arms and fingers. For example, manganese steel arms may be welded to the bars, in such case the arms including a stirrup portion D³ passing about the bottom of the bar C and joining the arms D on opposite sides of the bar. The bars may also be provided with bottom reinforcing members D⁴ from which laterally extend finger reinforcing members D⁵. It will be seen as from Figures 1 and 2 that the arms extending laterally from adjacent bars inter-penetrate, and that the fingers of adjacent arms inter-penetrate in such fashion that a previous separating bed is provided with a plurality of apertures. In the form of the device herein shown these apertures are uniformly distributed and are of uniform size, but a slight variation in size, shape and distribution may be made in a given separating bed if necessary.

Referring for example to Figures 1 and 2 it will be seen that extending longitudinally of the separating bed, and aligned along the upper surface of the various arms, are upwardly extending ridges E. The ridge for each pair of arms extends from the end of one arm across the bar and to the end of the opposite arm. The aligned portion of the next bar is provided between its arms with a corresponding ridge portion E¹, whereby in effect a plurality of continuous ridges extend from end to end of the separating bed, having for effect to support a larger or the flatter pieces slightly above the surface of the separating bed. Along the end arms of each bar is an even higher terminal or boundary ridge E² within which depends a preferably flexible wall member E³ which may be mounted on any suitable brackets or supports E⁴, which in turn are secured to one of the side members A¹ or A². The brackets may carry

a longitudinally extending plate or plates E⁵ to which the flexible member E³ may be bolted or otherwise secured. The brackets E⁴ may be adjusted as by the slots E⁶ through which pass any suitable securing members E⁷. On the end bars of the bed, as shown in Figure 1, only inwardly projecting fingers need be used, so that the ends of the bed are actually defined by bars and not by outwardly projecting fingers.

In order to impart to the bars an oscillating movement, I provide a longitudinal rocker arm extending along one or both sides of the separating bed. I illustrate it herein only along one side of the bed as in normal use a single rocker arm is sufficient, but it will be understood that if necessary a corresponding and substantially identical arm may be positioned along the opposite side of the bed. I illustrate for example an arm including a channel G having a bottom portion G¹ and upwardly extending side portions or flanges G². Extending across said arm between the side flanges G² are a plurality of tubes or cylinders G³, one for each bar to be oscillated. Surrounding each said cylinder G³ is a bushing G⁴ preferably of rubber or some suitable yielding material. Clamped about said bushing and connecting it with the corresponding bar to be oscillated is an arm generally indicated as G⁵ which includes opposite parts G⁶, G⁷, such parts being clamped or secured together about the outwardly extending enlarged portion of the shaft and about said bushing. To connect the members G⁶ to the bar, I may provide an upper securing bolt G⁷ which passes through the enlarged end portion of the bar, and lower securing bolt G⁸ which passes beneath it. At the lower end of the members G⁶, I may provide a single securing bolt G⁹ with its securing nut G¹⁰ which draws together about the bushing G⁴ the arcuate clamping elements G¹¹. It will be understood that the pressure upon the bushing G⁴ may be varied or adjusted, as by varying the thickness of number of the shims G¹² as shown in Figure 3. It will be understood that the parts are so drawn up or secured that the rubber bushing G⁴ is held against rotation to the cylinder G³ and is also held against rotation in relation to the surrounding members G¹¹ of the arm G⁵. In other words, relative movement of the parts causing internal torsion of the rubber and relative rotation or movement of opposed abutting surfaces of rubber and metal.

In order to move the bar G as a whole, I provide the below described connection, namely a bar of opposed and generally triangular plates H¹ H² which depend from the bar G as shown in Figures 3 and 4. These plates are laterally outwardly inclined somewhat as at H¹ H² and may be reinforced at their lower portion as at H² to receive the tube or cylinder H³. This cylinder in turn

has about it the rubber bushing H^4 about which are clamped the opposed arcuate stirrups H^5 H^6 at the end of an actuating eccentric arm below described. H^7 are any suitable bolts with the nuts H^8 , whereby the pressure about the bushing H^4 may be adjusted, as for example through the shims H^9 . The structure above described may be seated upon the tapered end H^{11} of the eccentric arm H^{10} , to which it may be secured as by the nut H^{12} . It will be noted that the nut H^{12} is mounted with a separate member H^{13} through which pass the ends of the bolts H^7 and which abuts against the member H^5 , being separated from it for example by additional adjusting shims H^{14} .

I may employ any suitable means for actuating the arm H^{10} . But since the details of such actuating means do not of themselves form part of the present invention they are not described in detail.

It will be realized that whereas I have described and shown a practical and operative means for carrying out my invention, that nevertheless many changes in size, shape, number and disposition of parts may be made, and that my process may be carried out with a variety of different structures. I wish my description and drawings to be taken, therefore, as in a broad sense diagrammatic or illustrative, rather than as limiting me to my precise showing herein.

The use and operation of my invention are as follows:

I maintain a separating bed or zone of separation wherein opposed bounding walls of individual screening apertures are given a positively controlled and limited differential movement, along lines or directions generally perpendicular to the plane of the bed or zone. I maintain a movement of relatively short excursion and of relatively high velocity, my experience being that a slow movement and a long travel causes grinding rather than clean cut separating or screening. When I employ a short travel and high frequency, the particles are not ground, but either pass through the apertures or are else kicked out. A particle may not go through an aperture unless it is small enough to fall freely through the aperture. If it barely fits an aperture, in such a way that grinding will result, it is immediately kicked out and goes on to try the next hole and, if even slightly oversize, passes entirely across the separating zone.

The zone is formed by a series of screen bars having interpenetrating arms and fingers, as herein shown. Each individual bar is oscillated about a pivot or axis, all the bars being oscillated in a like rotational direction. The result is that the opposed arms and fingers of adjacent bars are continually moving in opposite directions, except at the time of the dead points of change of

direction. Also, while the arc of travel of each arm increases outwardly from its central rotation, the relation between the opposed walls of adjacent arms and fingers of different bars is always the same because the maximum travel at the end of one bar takes place adjacent the minimum travel of the adjacent bar or arm, and the relative movement between opposed sides of the individual apertures is uniform.

When I wish to separate material having particles with a wide range in size, for example when a mass of larger particles or fragments, mixed with fines, is to be separated, a large particle, for example, a flat fragment, if it slides along the surface of the bed, might temporarily blind many of the apertures. I therefore provide means for spacing these excess oversize particles upwardly away from the screen surface. Hence the ridges E , E^1 which extend longitudinally from end to end of the separating bed and which project upwardly above the normal surface of the tops of bars, arms and fingers. These ridges carry the big particles as they travel along the screen and space them upwardly away from the screen openings so that the small particles which sift down to the bottom of the mixed mass are screened out or separated without even a temporary blinding of the separating apertures.

Conventional screening, with a screen body vibrated as a unit, raises and lowers the entire sheet of material being screened, causing the entire mass to travel by jerks. In my present separating bed the upward propelling force is not directed against the entire mass simultaneously, but against individual particles, or individual groups of particles. As a result, something of the effect of an air separator is obtained, and it is unnecessary bodily to displace the entire mass. As the arms and fingers on one side of each rod rise, the arms and fingers on the opposite side drop. The very coarse material being, in effect, screened out by the above mentioned ridges, the fines have free access to the separating apertures, and pass therethrough. As a result a very complete segregation of the fines from a body of particles of mixed sizes may take place without a preliminary coarse screening and without preliminary separation or removal of the larger particles. In effect the result both of a bar grizzly and of an attendant or following screen is obtained and my bed or zone of separation maintains in effect two separate screening planes, both in the same material bed or zone of separation and both carried by and oscillated by the same supporting and actuating mechanism. For example, in feeding mixed materials to a cone crusher, it may be desirable to crush particles of diameters as high as nine inches or more. Assume that such materials have to be crushed to a size say of

one inch, but are accompanied by a substantial volume of particles already reduced to a size of one inch or less. I may pass the mixed materials over a separating bed the diameters of the apertures of which are, say, one inch. These apertures will permit the undersized material to escape, while all material above one inch will pass over the separating bed, and may be conveyed to the 10 crusher. Not only will my separating bed screen out the fines, but it will support the impact and weight of the large boulders from which the fines are separated. I may freely feed heavy jagged rocks to my bed, and separate 15 the fines. I may, for example, employ bars of manganese steel, which bars will efficiently resist deformation or breakage, and which will have a long life of wear. If ordinary screen cloth were employed, the heavy 20 jagged boulders would quickly batter the mesh to pieces.

In connection with the structure employed, I provide practically unbreakable means for not only spacing the larger particles away 25 from the separation zone of the bed, but from preventing them from damaging the separating members. The manganese steel bars and fingers are as effective as or more effective in separation than screen cloth, and 30 can resist the punishment of large boulders in the way in which screen cloth cannot.

I claim:

1. In a separating bar, a longitudinally extending bar member, arms extending laterally from opposite sides of said bar, fingers laterally extending from opposite sides of the arms, and ridges upwardly extending along the tops of the arms, the tops of the ridges, and the upper faces of the arms, defining generally parallel planes, the arms along opposite sides of the bars being in line, the fingers of adjacent arms and of opposite sides of the same arm being aligned, and a terminal extension at each end of each 45 said bar, extending outwardly beyond the junction of the outermost arm with the bar, the outermost arm being provided with a flange upwardly extending to a height somewhat greater than the height of the ridges upon 50 the remaining arms, the terminal extensions extending upwardly above the normal plane of the tops of the fingers.

2. In a separating bar, a longitudinally extending bar member, arms extending laterally from opposite sides of said bar, fingers laterally extending from opposite sides of the arms, and ridges upwardly extending along the tops of the arms, the tops of the ridges and the upper faces of the arms, defining generally parallel planes, the arms along opposite sides of the bars being in line, the fingers of adjacent arms and of opposite sides of the same arm being aligned, and a terminal extension at each end of each 60 said bar, extending outwardly beyond the junction of the outermost arm with the bar, the outermost arm being provided with a flange upwardly extending to a height somewhat greater than the height of the ridges upon the remaining arms, the terminal extensions extending upwardly above the normal plane of the tops of the fingers.

3. In a separating bar, a longitudinally extending bar member, arms extending laterally from opposite sides of said bar, fingers laterally extending from opposite sides of the arms, and ridges upwardly extending along the tops of the arms, the tops of the ridges, and the upper faces of the arms, defining generally parallel planes, the arms along opposite sides of the bars being in line, the fingers of the adjacent arms and of opposite sides of the same arm being aligned.

4. In a separating bar, a longitudinally extending bar member, arms extending laterally from opposite sides of said bar, fingers laterally extending from opposite sides of the arms, and ridges upwardly extending along the tops of the arms, the tops of the ridges, and the upper faces of the arms, defining generally parallel planes, the arms along opposite sides of the bars being in line, the fingers of the adjacent arms and of opposite sides of the same arm being aligned.

5. In a separating bar, a longitudinally extending bar member, arms extending laterally from opposite sides of said bar, fingers laterally extending from opposite sides of the arms, and ridges upwardly extending along the tops of the arms, the tops of the ridges, and the upper faces of the arms, defining generally parallel planes, the arms along opposite sides of the bars being in line.

6. In a separating member adapted for use in a separating bed, a longitudinally extending bar, a plurality of arms extending from opposite sides of the bar, and a plurality of fingers extending from opposite sides of the arms defining a single plane, said bar extending outwardly longitudinally beyond said arms and fingers, said outwardly extending portion of the bar extending upwardly above the normal plane of the upper faces of bar, arms and fingers.

7. In a separating bar, a longitudinally extending bar member, arms extending laterally from opposite sides of said bar member, each said arm including a web portion and a reinforcing rib therebeneath, of greater depth but of less width than such web portion, fingers laterally extending from opposite sides of the arms, the fingers including web portions lying in the plane of the webs of the arms and reinforcing ribs positioned therebeneath and associated with the reinforcing ribs of the arms.

8. In a separating bar, a longitudinally extending bar member, arms extending laterally from opposite sides of said bar member, each said arm including a web portion and a reinforcing rib therebeneath, of greater depth but of less width than such web portion, fingers laterally extending from opposite sides of the arms, the fingers including web

125 portions lying in the plane of the webs of the arms and reinforcing ribs positioned therebeneath and associated with the reinforcing ribs of the arms.

portions lying in the plane of the webs of the arms and reinforcing ribs positioned therebeneath and associated with the reinforcing ribs of the arms, and ridges upwardly extending along said arms, the upper surfaces of said ridges defining a plane generally parallel with the plane of the web portions of fingers and arms.

Signed at Hollywood county of Los Angeles and State of California, this 11th day of December 1930.
